UNITED STATES PATENT OFFICE.

LUCIEN I. YEOMANS, OF CHICAGO, ILLINOIS, ASSIGNOR TO AMALGAMATED MACHINERY CORPORATION, OF CHICAGO, ILLINOIS, A CORPORATION OF NEW YORK.

COMBINED MACHINE-TOOL AND CRANE.

1,286,867.

Specification of Letters Patent. Patented Dec. 3, 1918.

Application filed March 3, 1916, Serial No. 81,804. Renewed October 11, 1918. Serial No. 257,792.

To all whom it may concern:

Be it known that I, LUCIEN I. YEOMANS, a citizen of the United States, residing at Chicago, in the county of Cook and State of Illinois, have invented a certain new and useful Combined Machine-Tool and Crane, of which the following is a specification.

The object of this invention is to provide a machine tool, as for example, a lathe, with improved means to facilitate the operation 10 of placing work in the machine and of removing the finished pieces.

In the accompanying drawings Figure 1 is a perspective fragmental view of a combination lathe and crane embodying the features of my invention. Fig. 2 is a view of one of the tongs or grapples of the crane.

In the drawings, 1 denotes the bed or frame of the lathe, 2 the chuck or face plate carried by the head stock, 3 the dead center carried by the tail stock, and 4 the tool rest or carriage. An upright 5 is rigidly secured to the framework of the lathe. An arm 6 is pivotally supported upon the upper 20 end of the upright 5 for pivotal movement in a horizontal plane. To the free end of the arm 6 is secured a vertical spindle or pivot 7 extending downwardly from the arm. A carrier 8 is pivotally or swiveled, 25 mounted intermediate its ends upon the pivot 7 for rotation in a horizontal plane. At the opposite ends of the carrier 8 are sheaves 9 carrying a rope or cable 10, which is free to be reciprocated in said sheaves. 30 To the opposite ends of the cable 10 are secured grapples or tongs 11 of any suitable construction. Each tong 11 is adapted to embrace and support a piece of work of the kind for which the machine tool is intended, 35 as for example, the case of an explosive shell.

In the embodiment herein shown, 12 are the jaws of the tongs, 13 the handles, 14 are links pivotally connecting the handles to the lower end of a bar 15, and 16 is a hand-lever 40 pivoted to the upper end of the bar 15 and connected intermediate its ends to the end of the cable. 17 is a pivoted latch to lock the handle in the position shown in the several views. Preferably, the cable 10 is of such 45 length that when one of the tongs is in engagement with a shell case lying upon the floor and the handle of that tongs is up, the other tongs is at the right height to engage 50 a shell case held by the lathe centers, the

hand-lever of the last mentioned tongs being 55 down.

While the manner of using the crane may be varied, one method is as follows: Assume that the handle of the tongs *c* is up; that said tongs is in engagement with a case *b* 60 lying on the floor beside the lathe. Assume also that the handle of the tongs *d* is down. The tongs *d* is then at the right height to grasp the case *a* which has just been turned in the lathe. The tongs *d* is engaged with 65 the case *a*. The handle of the tongs *c* is turned down. The case *a* is then released from the lathe centers, and swung toward the front of the machine, the arm 8 turning 70 upon its pivot 7 and the arm 6 turning 70 upon the upright 5. Inasmuch as the weights carried by the opposite ends of the cable 10 are equal save for the material removed from the case *a* in the lathe, it will 75 be seen that to raise the case *b* into the horizontal plane of the lathe centers, the operator needs merely to exert enough force to compensate for the material removed in the lathe. The case *b* having been raised into the horizontal plane of the lathe centers, 80 said case is swung into position between the centers, the arm 6 and carrier 8 revolving to the required extent. The case *b* having been chucked in the machine, the tongs *c* are released from the case *b* and swung clear 85 of the machine. While the case *b* is being turned in the lathe, the operator disengages the case *a* from the tongs *d* and engages said tongs with another case to be turned. As 90 soon as the case *b* has been turned, the operator places the tongs *c* in engagement therewith and removes said case *b* from the lathe as hereinbefore described.

It will be seen that the lathe and its crane constitute a unitary, self-contained structure, thus obviating the necessity of providing special supports in the building for the crane. It will also be evident that the pivoted arms 6 and 8 permit the pieces operated upon to be raised and lowered and 100 swung into and out of position between the lathe centers with a minimum of exertion on the part of the operator. Moreover, the idle periods of the machine are reduced to a minimum, as the piece just finished may be 105 removed from the tongs and another piece substituted in said tongs while the lathe is operating upon still another piece.

I claim as my invention:

1. The combination of a machine tool, an upright supported thereby, an arm pivoted to said upright to swing in a horizontal plane, a carrier swiveled to said arm and positioned to swing in a horizontal plane relatively to the arm, a cable reciprocably supported by said carrier and freely movable therein, and work-engaging devices attached to the respective ends of the cable, whereby either work-engaging device is raised as the other is lowered.
2. The combination of a machine tool, an upright supported thereby, an arm pivoted at one end to said upright to swing in a hori-

zontal plane, a vertically-disposed bolt secured to the other end of said arm, a carrier having means between the ends thereof to rotatably engage said bolt to swing in a horizontal plane relatively to the arm, a cable reciprocably supported by said carrier and freely movable therein, and work-engaging devices attached to the respective ends of the cable, whereby either work-engaging device is raised as the other is lowered.

In testimony whereof, I have hereunto set my hand.

LUCIEN I. YEOMANS.
